MAGNETIC ELEMENT MEMORY MATRIX

Munro King Haynes, Poughkeepsie, N. Y., assignor to International Business Machines Corporation, New York, N. Y., a corporation of New York

Application August 25, 1953, Serial No. 376,300

7 Claims. (Cl. 340—174)

This invention relates to magnetic storage systems and particularly to means for electrically receiving and magnetically registering and for electrically transmitting coded information.

An essential component of large scale digital computers is a memory device or a registering means for receiving information in the form of "words" each consisting of a plurality of "bits," often expressed in binary notation, and for storing this information over indefinite periods coupled with the facility for giving up this information on demand.

The object of the present invention is to provide extremely high speed means for simultaneously locating a given register and for "writing" therein a given word, consisting of a large plurality of bits or for locating such a register and for extracting and transmitting registered information therefrom. This object comprehends the transmission into or out of the register, of all the bits of a word simultaneously, that is, in parallel relation and within a time interval measured in terms of microseconds. Since the utility of such a device depends on its speed of operation, the object of the present invention is primarily to increase the speed thereof.

The present invention is based on the properties of a known type of magnetic material, spoken of as a bistable magnetic element, that is, a core of magnetic material having high retentivity whereby the remanent flux retained after saturation remains at practically the same value as at saturation. Such an element may be saturated in one direction to establish one magnetic state and later saturated in the other direction to establish a different state, whereby such an element by being driven alternately and selectively to one or the other state may be employed to register the two conditions necessary as a binary element. By using a winding about such a core to produce a positive or a negative magnetomotive force, the magnetic state of the core may be changed at will and, by using another winding, a change of state may be detected in the form of a pulse during such change in state.

A device of this nature is advantageous for several reasons. First, such magnetic cores require no steady state power such as the plate dissipation of an electronic trigger or the holding current for a relay. Second, they require no filament power and consequently generate negligible heat. Third, magnetic cores can be made quite small, that is, in the order of three eighths of an inch outside diameter and one quarter inch long and because of their low power dissipation they may be stacked in compact arrays. Fourth, the service life of a physically protected core is essentially infinite. Fifth, a core's "memory" is substantially unlimited and is independent of power line failures, and sixth, a winding on a core is a two terminal device and therefore it can be switched in two dimensions simultaneously.

In accordance with the present invention a large number of such magnetic elements may be arranged in a multiple matrix or cubical array, constituting a plurality

2

of registers each providing facilities for registering a word having a plurality of bits, the number of registers and the number of word bits being arranged in accordance with the use for which the device will be employed.

5 The device is spoken of as a multidimensional magnetic storage element and, by way of example, finds employment as a memory organ in large scale digital computers.

Further, in accordance with the present invention, a three dimensional arrangement is provided whereby identification of two dimensions may be used as the address of any particular register and operation through the third dimension will selectively operate the various elements of the identified register in accordance with the character of the corresponding word bits. The two address variables select a register or what may be termed a "word line" and a diode in this line prevents sneak paths in the matrix connections. These word lines each extend through a plurality of planes each of which represents a word bit so that the selection or the electrical characterization of each plane has a corresponding effect on the selected word line as it passes through such plane.

15 Each word line consists of a plurality of magnetic cores equal in number to the number of word bits for which provision is made and a winding for each core, connected in series along the word line, provides a circuit, one end of which may be selected by a first variable and the other end of which may be selected by a second variable. Additionally, a second winding is provided for every core in any given plane and these, being all placed in a series circuit, may be selectively energized to add to or subtract from the energizations in their associated core windings. Thus, if the word line coils are all positively energized sufficiently to positively saturate the cores, and then the word bit coils for one word bit are all positively energized but insufficiently themselves to positively saturate the cores, it will appear that that core in which these effects are added will be amply positively energized while all other cores in the said word bit plane will not be affected. If, at another word bit plane, a negative energization is applied to all word bit coils in that plane, but insufficiently to negatively saturate the cores therein, then no core in that plane will be affected, including the particular selected word line bit core. This core will have a resultant weak positive energization while all other cores in that bit plane will have a weak negative energization, insufficient to disturb any positive state previously established therein.

20 A feature of the invention is a circuit arrangement of coils in a matrix whereby a significantly great energization of a core may be produced. Heretofore a two to one ratio was the best that could be produced in any prior art arrangement which rendered the action comparatively slow (about 700 microseconds with known magnetic materials). In accordance with the present feature a three to one ratio can be achieved and therefore since a greater energization can be applied to the cores, the time taken to achieve saturation is greatly reduced (in the order of 50 microseconds with the same magnetic materials).

25 In accordance with this feature a circuit arrangement is employed whereby current will flow in the coils of but a single word line so that the magnitude of this current may be larger than in the usual matrix array where a limit is set by the algebraic sum of this and other currents in the coils of other word lines. Where one unit of magnetomotive force is insufficient to cause a change in state in a core of magnetic material and where two units will be sufficient for the purpose, it has not heretofore been possible to provide a combination of currents in the different coils of a magnetic element greater than two units. However, due to the fact that a unique selection of but a single word line is made the current transmitted through

this word line may be much larger than heretofore. By transmitting current through the bit coils (connected in series with bit coils of other word lines) to add to or subtract from the effects of the current transmitted through the word line coils, a greater algebraic sum may be achieved. Thus, if current for two units of energization is transmitted through the word line coils a change of state may be accomplished by transmitting another unit through the bit coil making an algebraic sum of three units while allowing but a single unit in the other bit coils of the same level, thus leaving the other bit plane cores unaffected. Likewise when a particular core of the selected word line is to be left unaffected, an inhibiting current for one unit of magnetization is transmitted to the bit coils of a corresponding level so that the algebraic sum in the selected word line core is but a single unit whereby that core is left unaffected and the other bit coils of the same level have a negative single unit and they also are left unaffected.

By means of this arrangement a three to one ratio is obtained whereby a change of state may be brought about in a lessened time interval.

Another feature of the invention is a circuit arrangement whereby the coils of a word line may be energized in a given direction while the bit coils associated therewith may be selectively and directionally energized whereby the resultant energization of the cores of a word line may be selectively and separately made to be the sum or the difference of two simultaneously applied energizations thereof.

Another feature of the invention is the coincident selection of the two ends of the coil circuit for a word line whereby the elaborate precautions heretofore taken to guard against the effect of sneak paths in a matrix are largely eliminated, it now being necessary to provide but a single diode in each word line circuit.

Another feature of the invention is an alternative circuit arrangement whereby regenerative means is provided to amplify or fortify the energization of a core when and if the energization applied thereto is sufficient to produce a change in state whereby the complete operation may be insured and the speed thereof greatly increased. In accordance with this feature an extra winding and a transistor are provided for each core, the transistor acting upon the effective change in state of a core to detect such a change and to fortify it whereby the operation is accomplished in a lessened time.

Other features will appear hereinafter.

The drawings consist of three sheets having five figures, as follows:

Fig. 1 is an idealized hysteresis loop showing the most desirable type of magnetic material which may be employed for the purposes of the present invention.

Fig. 2 is a schematic circuit diagram showing how one of two magnetic elements may be driven through a change in magnetic state, while the other of the two remains unaffected.

Fig. 3 is a schematic circuit diagram represented in isometric projection to show how eight magnetic elements may be arranged in a cubical array of four word lines, each having two bits and how these word lines may be selected through two of the dimensions of such cubical array and the bits thereof selectively activated through the third dimension thereof.

Fig. 4 is a fragmentary schematic circuit diagram showing how a change of state of a magnetic element may be magnified and fortified by a semi-conductor amplifier, and.

Fig. 5 is a schematic circuit diagram, drawn with certain elements of isometric projection to give reality to the three dimension allusions in the description of the circuit, and showing the use of transistors in the word bit circuits of a single word line circuit.

Fig. 1 is an idealized hysteresis curve of the magnetic material used for the purposes of this invention and is a

close approximation to what may actually be obtained in practice. It has high retentivity so that if it is positively saturated at some time to the point *e* it will retain a flux density represented by the point *f*. Let us assume that it is in the state to represent binary 0, that is, it has been negatively saturated to the point *j* and then relaxed to the point *a*. Now if a magnetomotive force sufficient to saturate it in the positive direction is applied the curve *a b c d e* will be traced and when this energization is relaxed it will return to the point *f*. In this state it will represent binary 1. If thereafter it is again positively energized toward saturation at *e*, either slightly or very strongly, no change in state will occur, the material returning in any case to the state at *f*. Likewise, if the material is energized negatively toward *g*, but not sufficiently to reach the point *g*, no change in the state will occur, the material returning to the state at *f*. However, if the material is negatively energized more than sufficiently to reach the point *g*, then the curve *f g h i j* will be traced and when the energization is relaxed the material will return to the state represented by the point *a*.

For purposes of further discussion it will be noted that from point *a* an energization of $+H_1$ is insufficient to cause a change in state, but an energization of $+2H_1$ or more will drive the material to saturation and then on relaxation to point *f*. Likewise an energization of $-H_1$ will not cause a change of state from point *f*, but an energization of $-2H_1$ or more will cause a change of state, leaving the material finally at point *a*.

Fig. 2 is a circuit diagram used as an example of a means whereby information in the form of binary states may be stored. There are shown two cores 1 and 2 of material having the characteristics depicted in Fig. 1. Each core is provided with two energizing windings, the winding 3 of core 1 and the winding 4 of core 2 being in series and in circuit with the tubes 5 and 6. When these tubes are rendered conductive, sufficient current will flow through the windings 3 and 4 to provide a positive magnetomotive force in the associated cores 1 and 2 respectively, a value of $+2H_1$. These cores are also provided with another winding, 7 on core 1 and 8 on core 2. Assuming that both the cores are at binary 0, that is, both are in the state represented by the point *a* in Fig. 1, then, if coil 7 is connected in a circuit so that sufficient current will flow to provide an energization of $+H_1$, and this is done while the coil 3 is energized, then the resultant energization will be $+3H_1$ and the core will be driven to the point *e* or beyond so that upon relaxation this core 1 will return to the state represented by the point *f*, representing binary 1. Likewise, if coil 8 is connected in a circuit whereby sufficient current will flow to provide an energization of $-H_1$ and this is done while the coil 4 is energized, then the resultant energization will be $+H_1$ and the state of the core 2 will not be changed so that upon relaxation this core 2 will return to the state represented by the point *a*, representing binary 0.

The rest of the circuit is a means whereby the energization of the coils above described may be produced. A relay 9 is provided in a circuit with a circuit maker 10 and a battery so that upon the operation of this circuit maker the relay 9 will be operated. A condenser 11 is normally connected in series with a resistance 12 and is normally charged to the potential of the battery 13. Upon the operation of the relay 9 the condenser 11 is connected in circuit with a resistance 14 and a relay 15. As a result the condenser discharges through the relay 15 and the relay 15 operates transiently and for a very brief period. During this period a positive potential is applied to the grids of tubes 5 and 6 and a pulse of current will flow through the coils 3 and 4. At the same time coil 7 is connected in a circuit to energize the core 1 positively and the coil 8 is connected in a circuit to energize the core 2 negatively. Thus a transient energization of the various coils is produced in the manner described.

The circuit of Fig. 2 does not purport to represent any

particularly useful arrangement but is submitted for the purpose of showing how the cores may be driven to one or the other state by the coincident application of appropriate positive or negative pulses to different parts of the circuit and it will render the following schematic circuits easily understood with a minimum of circuit detail. The relay 9, marked select means, represents the means for selecting the particular tubes, such as the tubes 5 and 6, and for applying current pulses of the proper polarity to the word bit coils such as the coils 7 and 8. The relay 15 represents the pulse means, that is the means which will be employed to produce and transmit the several pulses simultaneously. It will be realized that a relay such as relay 15 could not in practice be used for this purpose as it is much too slow for the high speed operation possible in the employment of the magnetic core elements of the present invention. Fig. 2, however, will serve to show how such elements may be controlled.

Applicant proposes that a large array of coils to constitute a plurality of registers or word lines, each having a plurality of coils corresponding to word bits be interconnected in a circuit configuration which may be represented in the three dimensions of an isometric drawing. A line which may be the intersection of a plane perpendicular to advance in the X direction with a plane perpendicular to advance in the Y direction, will represent the coil circuit of Fig. 2. Each coil therein represents an intersection of this line with a plane perpendicular to advance in the Z direction. The various word lines are interconnected in a matrix and therefore a diode must be placed in each word line to prevent sneak paths.

Fig. 3 is a representation of what may be termed a three dimensional array of four word lines each having means for storing two word bits. A practical device for a large scale computer might have as many as 4096 word lines (64 X planes and 64 Y planes) each of 40 bits (40 Z planes), but this 2 by 2 by 2 arrangement of Fig. 3 will serve to illustrate the principle employed.

In this figure, eight cores 20 to 27 inclusive are shown. It will be noted that cores 20, 22, 24 and 26 are in the same X plane, that cores 20, 21, 24 and 25 are in the same Y plane and that cores 20, 21, 22 and 23 are in the same Z plane. Thus, by the X selection of conductor 28 and the Y selection of conductor 29, the word line consisting of cores 20 and 24 may be selected. Through the selective connections applied to the various Z planes the cores 20 and 24 may be selectively affected.

Each core is shown with three coils, one for writing, one for reading and one for the selective registration of a word bit in that particular core. Thus, core 20 is provided with a coil 30 in the write circuit, coil 31 in the read circuit and coil 32 in the Z1 plane for the Z1 bit. Each of these coils is characterized by a dot to indicate polarity, and it will be noted that the polarity of the read coil 31 is opposed to that of the write coil 30. The connections of all the Z coils is the same so that the polarity of the coils in the various Z planes is controlled outside the matrix by selective application of energizing current to the connections for each such plane.

Now if a word is to be registered in the word line represented by the cores 20 and 24, the connections 28 and 29 are selected and the write control conductor 33 is employed, whereby tubes 34 and 35 are rendered operative. The current carrying capacity of this circuit from plus battery through tube 34, coil 30, coil 36 of core 24, diode 37, and tube 35 to ground is such that each of the cores 20 and 24 will be energized by a magnetomotive force of $+2H_1$ (see Fig. 1). Due to the diode 37 no sneak paths may be established. This energization of the cores is sufficient to affect a change of state therein assuming they are both in the state to represent binary 0. However, the possible change of state depends on the simultaneous action of coils 32 and 38. If it is assumed that at this time the coil 32 is energized to provide a

magnetomotive force in the core 20 of $+H_1$, then the resultant therein is $+3H_1$ and a change of state will be produced. A magnetomotive force of $+H_1$ will also be produced in the other cores 21, 22 and 23 of the Z1 plane but this is insufficient to affect the state of any of these cores and so will not disturb the corresponding bits of words written therein in some other previous operation. If it is assumed that at this same time the coil 38 is energized to provide a magnetomotive force in the core 24 of $-H_1$, then the resultant force therein will be $+H_1 (+2H_1 - H_1)$ and no change of state in the core 24 will be produced. At the same time the other cores 25, 26 and 27 in the ZN plane will be energized to $-H_1$, but this is insufficient to cause any change in state in these cores regardless of whether they have been previously driven to express binary 0 or binary 1.

It will also be seen from Fig. 3, that if the read conductor 39 is affected instead of the write conductor 33 that then, through the control means 40 the tube 41 instead of the tube 35 will be rendered conductive. In this case the read coils 31 and 42 will be energized instead of the write coils 30 and 36. Since the polarity of the read coils is opposed to that of the write coils each of the cores 20 and 24 may be given a $-2H_1$ energization, or more highly negative as desired. The Z plane coils are not concerned in the read operation and hence all cores in this word line will be driven to express binary 0.

By way of example, each of the cores may be supplied with a fourth coil such as the coil 43 on the core 20. As the core 20 changes its state from positive (binary 1) to negative (binary 0) the collapse of its positive field and the building up of its negative field will induce a pulse in the coil 43 which may be taken off into an appropriate circuit, where it may be usefully employed.

A pulse of opposite polarity will be induced in the coil 43 when the state of the core is being changed from binary 0 to binary 1, that is, during a "write" operation, which may be usefully employed when there is occasion for such an operation.

Thus it will be seen that by applicant's circuitry by which the coils of the selected word line alone are energized, a greater ratio of energization may be achieved. Heretofore, where the coils in the matrix were directly energized, the resultant energizations of other coils necessarily, had to be proportioned so that the algebraic sum of energizations of other coils, in the matrix but not in the selected word line, was always less than that necessary to produce a change in state with the consequence that a two to one ratio was the best that could be achieved. With applicant's coincident selection of the two ends of a word line circuit, it appears that a three to one ratio may be obtained (and an even greater ratio on the read operation). In consequence the speed of operation may be greatly increased, by way of example, from a value in the order of 700 microseconds to a value in the order of 50 microseconds.

Fig. 4 is a fragmentary schematic diagram by which the use of a transistor may be explained. A core 50 is shown having four windings 51, 52, 53 and 54. If, during a write operation, a negative potential is applied to the lower terminal of coil 53, the collector 55 will be rendered negative. If then a negative trigger pulse is applied to the base 56 of the transistor through the application of a write pulse to the coil 51, a regenerative action will be set up in the core 50, which is acting as a transformer. The voltage drop across the collector winding 53 induces a voltage in the base winding 52 such as to drive the base 56 more negative. This in turn allows more current to flow in the collector winding 53. This regenerative action continues until the core 50 is saturated, at which time no more voltage can be developed in the base winding 52 and the action collapses. Magnetomotive forces very much larger than H_1 are obtainable and write times of the order of 5

microseconds may be achieved with selected core materials and selected transistors.

A three dimensional storage system using transistor blocking oscillators is shown in Fig. 5. Here a single word line is shown consisting of the core 60 in the Z1 plane (for one word bit), core 61 in the Z2 plane for another word bit, and core 62 in the ZN plane for still another word bit. Through an X selection the tube 63 is rendered conductive and through a Y selection and the activation of the write control 64, the tube 65 is rendered conductive. Thereupon sufficient current is transmitted from a positive source of current, through the tube 63, thence through the coils 66, 67 and 68, the diode 69 and the tube 65 to ground whereby the cores 60, 61 and 62 are energized to +H₁, insufficient in itself to change the state of any one thereof. Now, let us assume that in the Z selection only the tube 70 is rendered conductive so that a negative potential is applied to the collector of transistor 71, and a negative trigger pulse is applied to the base coil 72 (the pulse through coil 67), then the regenerative effect above described and the write pulse through the coil 67 will be greatly fortified so that a change in state of the core 61 will be produced. It is assumed that the Z selection does not activate the tubes 73 and 74 so that no change in state is produced in cores 60 and 62.

When it is desired to read the word registered in the word line, the tubes 63 and 75 will be rendered conductive so that any core in this line which is in the state to express binary 1 will have its field reversed and as a consequence the read coil will be used to transmit a pulse. Thus, as the read pulse is passed through the coil 77 a read pulse will be delivered by the coil 78, connected in series with all other similar read coils in the same Z2 plane, to a circuit where it may be usefully employed, such as the calculating unit of a computer.

What is claimed is:

1. Apparatus for storing information electrically by selectively and directionally electromagnetizing each of a plurality of magnetic elements capable of retaining a high degree of the magnetization to which said elements are subjected, comprising a matrix connection of a plurality of series of said elements, a said series of said elements constituting a word line and each element of a said series constituting a word bit, a diode in each said word line to confine current flow therethrough to one direction, a first plurality of matrix connections each having a group of said word lines connected by one end of each of the word lines thereto and a second plurality of matrix connections each having a group of said word lines connected by the other end of each of the word lines thereto, said connections being so arranged that any one of said first plurality of matrix connections is connected to any one of said second plurality of matrix connections through but a single one of said word lines, means for selectively, concurrently and transiently transmitting an energizing current through a selected one of said word lines insufficient alone to change the state of any one of said magnetic elements of said word line, a plurality of word bit circuits each connected to the corresponding word bit elements of all said word lines, means for selectively, concurrently and transiently transmitting energizing current through said word bit circuits to produce an energization of an element concurrently energized through its said word line circuit and a semiconductor amplifier connected to each said magnetic element jointly responsive to its associated word bit circuit and to the energization of its said associated magnetic element for fortifying the energization thereof.

2. Apparatus according to claim 1, wherein the connections from a given matrix connection of said first plurality through a said word line to a given matrix connection of said second plurality includes a coil for each said element of said word line poled to provide a magnetization of said element in a direction to a state

to express binary 1, where said element is normally in a state to express binary 0.

3. Apparatus according to claim 1, wherein each said element of each said word line is provided with a semiconductor amplifier constituting said last means responsive to a change in magnetization of said element to fortify said change.

4. Apparatus according to claim 1, wherein each said word line comprises a plurality of elements, a coil on each said element connected in series with corresponding coils of other elements of the said word line poled for storage of information, a coil on each said element connected in series with corresponding coils of other elements of said word line poled for clearing said series of stored information, a coil on each said element connected in series with corresponding coils of all others of said plurality of series for aiding in the storage of information and a coil on each said element connected in series with corresponding coils of all others of said plurality of word lines for transmitting stored information from said one of said series.

5. Apparatus for storing information electrically by selectively and directionally electromagnetizing each of a plurality of magnetic elements capable of retaining a high degree of the magnetization to which said elements are subjected, comprising a matrix connection of a plurality of series of said elements, a said series of said elements constituting a word line and each element of a said series constituting a word bit, a diode in each said word line to confine current flow therethrough to one direction, a first plurality of matrix connections each having a group of said word lines connected by one end of each of the word lines thereto and a second plurality of matrix connections each having a group of said word lines connected by the other end of each of the word lines thereto, said connections being so arranged that any one of said first plurality of matrix connections is connected to any one of said second plurality of matrix connections through but a single one of said word lines, means for selectively, concurrently and transiently transmitting an energizing current through a selected one of said word lines insufficient alone to change the state of any one of said magnetic elements of said word line, a plurality of word bit circuits each connected to the corresponding word bit elements of all said word lines, means for selectively, concurrently and transiently transmitting energizing current through said word bit circuits to produce an energization of an element concurrently energized through its said word line circuit and a semiconductor amplifier connected to each said magnetic element jointly responsive to its associated word bit circuit and to the energization of its said associated magnetic element for fortifying the energization thereof.

6. Apparatus for storing information electrically by selectively and directionally electromagnetizing each of a plurality of magnetic elements capable of retaining a high degree of the magnetization to which said elements are subjected, comprising a matrix connection of a plurality of series of said elements, a said series of said elements constituting a word line and each element of a said series constituting a word bit, a diode in each said word line to confine current flow therethrough to one direction, a first plurality of matrix connections each having a group of said word lines connected by one end of each of the word lines thereto and a second plurality of matrix connections each having a group of said word lines connected by the other end of each of the word lines thereto, said connections being so arranged that any one of said first plurality of matrix connections is connected to any one of said second plurality of matrix connections through but a single one of said word lines, means for selectively, concurrently and transiently transmitting an energizing current through a selected one of said word lines insufficient alone to change the state of any one of said magnetic elements of said word line, a

plurality of word bit circuits each connected to the corresponding word bit elements of all said word lines, means for selectively, concurrently and transiently transmitting energizing current through said word bit circuits to produce an energization of an element concurrently energized through its said word line circuit, and a regenerative means associated with each said magnetic element for increasing the energization thereof beyond a sufficient energization, said means being jointly responsive to its said associated word bit circuit and to the 10 energization of its said associated magnetic element.

7. Apparatus for storing information magnetically in a matrix of magnetic elements each capable of retaining a high degree of the magnetization to which it is subjected, comprising a plurality of energizing coils on each 15 said element, a plurality of word line circuits each having therein a plurality of coils on different ones of said elements, a first plurality of matrix connections each having a group of word line circuits connected by one end thereto, a second plurality of matrix connections 20 each having a different group of word line circuits connected thereto by the other end thereof, said connections being so arranged that any one of said first plurality of matrix connections is connected to any one of said second plurality of matrix connections through but a single 25 one of said word lines, means for selecting, concurrently and transiently transmitting an energizing current through a selected one of said word line circuits insufficient alone to change the state of any one of said magnetic elements associated therewith, a semi-conductor amplifier associated with each said magnetic element having a pair of coils interlinked therewith, one of said coils connected 30

to said amplifier being for enabling said amplifier and being poled to respond to an energization of said word line coil and the other of said coils being oppositely poled to fortify the energization of said word line coil to a point more than sufficient to change the state of its associated magnetic element and a plurality of bit selecting circuits each associated with a corresponding bit element of said word lines, said bit selecting circuits being separately and selectively energized and being connected to said enabling coils whereby said amplifiers are controlled by the joint energization of a bit selecting circuit and a word line coil.
